UNITED STATES PATENT OFFICE.

CHARLES L. MERITHEW, OF MUIR, MICHIGAN.

EMERY-WHEEL.

SPECIFICATION forming part of Letters Patent No. 555,579, dated March 3, 1896.

Application filed May 4, 1895. Serial No. 548,171. (No model.)

To all whom it may concern:

Be it known that I, CHARLES L. MERITHEW, a citizen of the United States, residing at Muir, in the county of Ionia and State of Michigan, have invented certain new and useful Improvements in Emery-Wheels; and I do hereby declare the following to be a full, clear, and exact description of the invention, such as will enable others skilled in the art to 10 which it appertains to make and use the same.

My invention relates to improvements in emery-wheels, and particularly to improvements in means for supporting the same; and it consists in an adjustable back plate adapted 15 to protect the emery-wheel from breakage in consequence of the side pressure to which it is subjected in use, not only when the wheel is first used, but after its surface has been worn and its diameter lessened, and also in 20 improved means for securing said back plate and emery-disk tightly together, the construction and arrangement of the parts of which will be hereinafter fully described, and particularly pointed out in the claims.

25 Emery-wheels are usually made of relatively small thickness in consequence of the cost of the material, and in their use they are often subjected to great pressure. This pressure, as it is exerted from only one side, frequently results in the chipping off or breaking of the periphery of the wheel, thus necessitating the reshaping of the wheel before it can be used again.

To strengthen emery-wheels, it is customary 35 to employ a central backing-plate, which, however, is usually of a diameter much less than that of the entire wheel. While partial protection from strain is thus afforded, such protection is by no means complete, and in actual use the difficulty of breakage of the rim is often experienced with such wheels.

Occasionally emery-wheels are used in 45 which a back plate is provided extending to the extreme periphery of the disk. This arrangement is disadvantageous, because as soon as the disk is used sufficiently to wear off the curved edges of such plate the protection afforded thereby is much lessened.

One object of my invention is to provide a 50 back plate which shall be free from the disadvantages consequent to the use of such plates as are now constructed, and which will

afford a uniform protection throughout the entire wear of the emery-wheel, effectually removing the danger of premature breaking 55 of the periphery of the emery-wheel.

A further object of my invention is to provide improved means for closely connecting the backing-plate and the emery-wheel.

My invention consists, first, in attaching to 60 a central backing-plate of relatively small diameter adjustable extension rods or plates, which extend to the periphery of the emery-wheel, and which, as the wheel becomes worn, can be drawn inward, thus affording a uniform protection to the wheel throughout the 65 entire period of its use, and, second, in forming an opening at the center of the emery-disk and passing therethrough the conical end of a plug, which on its outer end bears a large 70 round plate adapted to furnish a support to the central portion of the emery-wheel. The conical end of the plug is screwed into a suitably-formed projection on the back plate, thus holding the parts firmly and securely to- 75 gether.

My invention is fully represented in the drawings which accompany and form a part of this application, in which the same reference-numerals refer to the same or corresponding parts, and in which—

Figure 1 is a sectional view of an emery-wheel with my improved supporting or backing-plate in position thereon. Fig. 2 is a like view, the extension portions of the backing- 85 plate being removed, other means than those shown in Fig. 1 being shown for more securely attaching the central backing-plate to the emery-wheel. Fig. 3 is a back view of my emery-wheel, showing a modified form of 90 my supporting-plate.

Referring to the drawings, 1 represents an emery disk or wheel. This may be made of any desired size or thickness. It may be made a solid wheel, as shown in Fig. 2, or a central 95 aperture may be provided, as shown in Fig. 1. The outer surface of this wheel is left perfectly plain, so as to facilitate the facing of the same. To the back or rear face of the wheel is attached a supporting plate or collar 100 2. This plate is of a diameter much less than that of the entire wheel. I have shown in the drawings two methods of securing and firmly attaching it to the emery-disk: In the con-

struction shown in Fig. 1, which is the preferable construction, the conical plug 15 is inserted through the central opening in the emery-disk. This conical plug is formed with a 5 screw-threaded portion 16, a straight portion 17 of a width equal to the thickness of the emery-disk, and an end flange or plate 18, which is of relatively large diameter and serves as a strengthening-plate to the front 10 surface of the emery-disk. The screw-threaded end 16 of the plug is screwed into the interiorly-screw-threaded hollow projection 19 formed on the supporting plate or collar 2, and the parts are thus firmly held together. 15 The plug 15 is formed either with a countersunk recess 20 or the raised lug 21 for the reception of the end of the wrench used to force it into position.

In Fig. 2 no such conical plug is used, but 20 instead a form of bolt 4 is used to attach the back plate to the emery-disk, which has on one end a broad bearing-plate which presses against the outer surface of the emery-wheel and effectually prevents the bolts 4 from being torn through the emery-disk and thus 25 separated therefrom.

The plate 2 is provided with a socket 5, by 30 which it can be secured or otherwise attached to the shaft. On the surface of the plate 2 are formed sockets through which extend the 35 adjustable extension-rods 6, which are provided with curved ends 7, adapted to fit over the recessed back surface 8 of the emery-wheel and to be adjusted in position by means 40 of the thumb-screws 9. As many of these rods may be used as desired. The support secured by the use of these rods is very perfect, and as they can be drawn inward as the rim or 45 periphery of the wheel becomes worn down such support extends throughout the entire life of the wheel. The support afforded by the rods is such as to remove all possibility of the wheel breaking by reason of the side pressure to which it is subjected in use, and the life of the wheel is very materially lengthened.

While I have thus described one construction by which an adjustable back-support for emery-wheels may be obtained, it is obvious 50 that other constructions are available, and in Fig. 3 is illustrated one of these constructions. In this figure the segmental rings or plates 11 are secured by the arms 10 to the central back plate 2. The arms 10 are formed 55 with slots extending lengthwise of the same, and thereby hold the rings or plates 11 in a fixed position. When the emery-wheel is first used, the rings or plates 11 are so adjusted as to extend to the periphery of the wheel. 60 As such periphery becomes worn, the plates

can be adjusted inward. They still afford, however, perfect protection from breakage. When the wheels become so far worn that their use is no longer necessary or advisable, they can be removed, and thus allow the emery-wheel to wear to the rim of the central backing-plate without at any time being subjected to the risk of breakage. 65

I have thus described my invention as used in connection with emery-wheels. It is also 70 applicable to the use of other wheels of like nature, although they may not be constructed of emery, and although I have already described two methods of providing an adjustable back-support for emery-wheels it is obvious 75 that other methods may be devised which will come within the scope of my invention; so that

What I claim as new, and desire to secure by Letters Patent, is— 80

1. The combination with a disk of emery or like substance, of a central back-supporting plate attached to the same, adjustable supporting devices attached thereto, and adapted to extend to the periphery of the disk, and 85 means for holding said adjustable devices in a fixed position, substantially as described.

2. The combination with a disk of emery or like substance, of the central back-supporting plate 2, the adjustable rods 6 extending therefrom, the thumb-screws 9 for holding the same in a fixed position, substantially 90 as described.

3. The combination of a disk of emery or like substance having a depressed back edge, 95 of a central back-supporting plate attached to the same, adjustable supporting devices attached thereto, and adapted to extend to the periphery of the disk and engage on the said depressed portion of the edge and means 100 for holding said adjustable device in a fixed position, substantially as described.

4. The combination with a disk of emery or like substance, having a central aperture therein, and a central back-supporting plate 105 having a hollow interiorly-screw-threaded conical depression formed on the same, and having adjustable supporting devices attached thereto, means for holding said adjustable devices in a fixed position, and a 110 plug adapted to be inserted through the aperture in the emery-disk and to engage the screw-threaded depression in said back plate, substantially as described.

In testimony whereof I affix my signature 115 in presence of two witnesses.
